UNITED STATES PATENT OFFICE.

JULIUS K. LUX, OF WASHINGTON, DISTRICT OF COLUMBIA.

OPERATING MEANS FOR CIRCUIT-CONTROLLING DEVICES.

No. 901,630.

Specification of Letters Patent.

Patented Oct. 20, 1908.

Application filed July 31, 1906. Serial No. 328,567.

To all whom it may concern:

Be it known that I, JULIUS K. LUX, a citizen of the United States, residing at Washington, in the District of Columbia, have invented certain new and useful Improvements in Operating Means for Circuit-Controlling Devices, of which the following is a specification.

My invention relates particularly to means for indicating the positions of the movable contact and to operating means or handles for operating circuit controlling devices; objects of the invention are to provide an operating and indicating means which may be moved or turned in either direction from its normal operative position without operating the movable contact, or injuriously affecting the operation of the device or the parts thereof, to insure against undue stresses to parts of the device, to provide indicating or operating means or both of these which may be interchangeably applied to devices of a given class, so that in their operative position they will uniformly have a predetermined position relative to the movable contacts thereby to indicate the open or other conditions of the circuits, said means being exterior to the cover for indicating the position of the movable contact the more conspicuously and unfailingly, while permitting the complete inclosure of the device so as to exclude dust, moisture, insects and the like. To provide in combination with the herein-described features a means for easily removing and applying the said cover, indicating means, and operating means with a limited number of separately detachable parts.

Other objects of my invention will appear hereinafter.

The herein-described invention is designed to be applied to switches in general and more particularly to switches wherein the handle is designed to move in two rotary directions to influence the movable contact. One example of which is described in the patent to M. G. W. Hart, #569,332, dated Oct. 13, 1896, and another example of which is shown in the reissue patent to Julius K. Lux, #12,490, dated May 29, 1906, it is also applicable to other forms of switches.

Figure 1, is a side view of one form of indicator and operating handle and related parts embodying my invention, parts being broken away, and the central portion shown in section, a cover and spindle are also

shown in part and broken away. Fig. 2, is a side view at about right angles to that in Fig. 1. Fig. 3, is a top plan view on a reduced scale of the handle and indicator shown in Fig. 1. Fig. 4, is a detail view of the collar F and a portion of the spindle, the latter being broken away to show means for fastening those parts together. Fig. 5, is a detail view of modified forms of the collar, and the tooth adapted to rotate the movable contact of a switch in one direction only, said handle when equipped with said modification will then turn freely in one rotary direction without operating the movable contact.

Referring to the drawings in detail, E indicates the handle proper to which a pointer G⁴ or other suitable indicating means is affixed the latter coacting with an indicator —N'— on a cover —N— to indicate the position of the switch. The handle E is of insulating material and has a metal bushing E⁹ molded therein so as to be integral or rigid therewith. The said metal bushing E⁹ has a projecting portion E² which will be hereinafter described.

E⁷ is a sleeve movable longitudinally within the bushing E⁹. The upper end of the sleeve E⁷ is enlarged to receive the flanged head of the screw E⁴; and the extremity of the enlarged part of sleeve E⁷ is spun or pressed over the flange of the screw E⁴ to unite the screw to the sleeve and allow free rotary movement of the former within the latter.

The head of the screw E⁴ is incased in insulation E³. It will be noted that the screw is permanently secured to the handle to reduce the number of detachable small parts that are easily lost or misplaced. The handle bearing the integral bushing E⁹ and the movable sleeve E⁷ may thus be placed freely upon the spindle G³ and while the handle and sleeve remain stationary the screw E⁴ may be turned home upon the screw threaded spindle to secure the handle as against removal from the spindle, while leaving the same free to turn upon the spindle G³ in either rotatable direction. The handle E is provided with a circular recess wherein the insulation part E² may enter when the handle E and the bushing E⁹ are moved upwardly upon the sleeve E⁷. It will be plain that the sleeve E⁷ and the screw part E³—E⁴ have substantially no perpendicular move-

ment relatively to the spindle G^3 ; and that the handle E and the integral bushing E^6 have a predetermined perpendicular movement upon the said sleeve E^7 . When the 5 screw part E^3-E^4 is screwed or jammed home on the screw thread the sleeve E^7 , the bushing E^6 , and the handle E may rotate freely upon the spindle G^3 .

E^5 , indicates a coiled spring disposed 10 about a recessed portion of the sleeve E^7 and within the bushing E^6 . One end of the said spring is enlarged so as to expand to engage in a groove inside the bushing E^6 , the other end of the said spring is in engagement with 15 an upper portion of the sleeve and the spring is compressed so that when the screw E^4 is home in the spindle the spring urges the bushing E^6 and the handle portion E , perpendicularly toward the operating mechanism 20 and holds the same close to the cover N . The spring connection between the bushing E^6 and the sleeve E^7 prevents those parts from having rotary movement relatively to each other and all of the handle parts excepting E^3-E^4 turn upon the spindle G^3 . The parts E^3 , E^4 move in unison with the spindle. From the foregoing it will be seen that the handle E and the bushing E^6 , with its projecting portion E^2 turn freely about 25 the spindle G^3 and have a spring pressed 30 movement parallel with the axis of the said shaft.

The portion E^2 is the driving and positioning connection between the indicating, 35 operating means and the mechanism or movable contact of the device. The said portion E^2 has oppositely disposed sides both of which are oblique relative to the axis of the shaft as shown in Fig. 2.

F , indicates a circular collar with a slot 40 formed therein, the sides of which slot fit the spindle and secure the collar and the spindle together to move as one piece. The tapered sides of the portion E^2 on the han- 45 dle fit into the said slot in the collar and the spring construction above referred to urges the part E^2 downwardly into the said slot in the collar to effect a driving and positioning engagement with the said collar and spindle and thereby with the moving parts 50 of the switch. The opposite oblique sides of the part $-E^2-$ abut against opposite sides of the slot in the part $-F-$ and constitute slip drive abutting connections be- 55 tween the rotary indicator and switch for positioning the indicator relatively to the switch and allowing the said indicator to rotate independently of the switch when power in excess of a predetermined amount 60 is applied to the handle to which the indicator is affixed, that is the coacting engaging faces of the part $-E^2-$ and collar $-F-$ slip by each other when such excess power is applied.

55 To remove the handle and indicator the

screw threaded piece E^3-E^4 is unscrewed whereupon all of the heretofore described parts are removable from the spindle as one piece, and all of the component parts thereof remain united so as to prevent their separation and possible loss while providing means for incasing with insulation all metal parts which extend above the cover N . The strength of the spring E^5 and the taper of the sides of the tooth E^2 are so adjusted to each other that when the movable contact becomes lodged in such manner as to prevent its turning in a given direction as by accidental disarrangement of parts of the device, the tooth E^2 will compress the spring E^5 , by riding upon the inclined side of the slotted part F , and out of the slot so as to rotate independently of the parts F and G^3 . The handle is designed to operate the device in either direction with predetermined forces 85 and if the device does not respond to the said given operating force then the handle will rotate without the device so as to prevent overstraining the parts. This feature of the operation is especially important and 90 valuable as applied to rocking or oscillatory movements of the type described in the patent last above referred to: since in that structure the movable contact may not rotate in both directions from its normal home positions. Covers for this class of devices are provided with notches so as to engage a projection on the base to hold the cover in a predetermined position. The words "On" 95 and "Off" are marked or affixed on the cover in suitable positions. It will be plain that this form of the device may have one edge of the collar so inclined that it will operate the movable contact in only one rotary direction, said handle having a free or 100 non-operating movement in the other rotary direction as shown in the modification— Fig. 5.

I have elected to embody in this case all broad or generic claims covering the spring 105 press handle and indicator connecting and releasing means.

What I claim is:

1. In an indicator for an inclosed electric switch, a cover and exterior rotary indicator 115 having a slip drive abutting connections with the switch for positioning the indicator relatively to the switch and allowing the indicator to rotate independently of the switch when power in excess of a predetermined amount is applied thereto.

2. In an operating means for an electric switch, a rotary handle, abutting means disposed at an angle to the plane of movement of said handle for operatively connecting the handle to the switch, said abutting means having coacting oblique engaging faces which allow the abutting faces to slip by each other when power in excess of a predetermined amount is applied to the handle. 130

3. An indicator for an inclosed electric switch, the same comprising indicating means exterior to the inclosing cover, means including a slip connection for positioning the said indicator relatively to the said switch, and yielding means for urging the said positioning means into operative position.
4. An operating means for an electric switch, the same comprising positioning means including a slip connection for connecting the said operating means to the said switch, and yielding means for urging the said positioning means into operative position.
5. An operating means for an electric switch, the same comprising a part removable from the switch, and a part for bearing the said removable part, one of the said parts having spring pressed means including a slip connection for connecting the said parts to operate the switch.
6. An operating means for an electric switch, the same comprising a spring pressed connection for normally driving the said switch and for releasing the said driving connection when power in excess of a predetermined amount is applied to the said operating means.
7. Operating means for an electric switch, the same comprising a driving connection and means having movement to interrupt said driving connection when power in excess of a certain predetermined amount is exerted on the said operating means.
8. Operating means for an electric switch, the same comprising a slip-drive connection between the operating means and switch and yielding means for urging the said driving connection into operative position.
9. An indicator for inclosed electric switches comprising an inclosing cover and indicating elements exterior thereto, one of said elements being movable relatively to the other in directions at substantially right angles to each other, and means including a slip-drive connection for positioning one of the elements relatively to the other.
10. An indicator for inclosed electric switches comprising an inclosing cover and indicating elements exterior thereto, one of the elements being movable in two directions at substantially right angles to each other relatively to the other element, means including a slip-drive connection for positioning the movable element relatively to the other element and yielding means for urging the positioning means into operative position.
11. In a rotary electric switch, a cover 60 having indicating characters thereon, a rotary indicator exterior to the cover, a spindle coaxial with the indicator, slip-drive connections between the indicator and spindle for positioning the indicator relatively to the switch and allowing said indicator to turn independently of the spindle when power in excess of a predetermined amount is applied to the indicator.
12. In a rotary electric switch, a cover 70 having indicating characters thereon, a rotary indicator exterior to the cover, a spindle coaxial with the indicator, slip-drive connections between the indicator and spindle for positioning the indicator relatively to the switch and allowing said indicator to turn independently of the spindle when power in excess of a predetermined amount is applied to the indicator, a handle 75 secured to the spindle and rotatable in one direction independently of said spindle.
13. In a rotary electric switch, a cover having indicating characters thereon, a rotary indicator exterior to the cover, a spindle coaxial with the indicator, slip-drive 85 connections between the indicator and spindle for positioning the indicator relatively to the switch and allowing said indicator to turn independently of the spindle when power in excess of a predetermined amount is applied to the indicator, a sleeve 90 coaxial with the indicator and spindle, and means between the sleeve and indicator for urging the slip-drive connection to its operative position.
14. In a rotary electric switch, a rotary spindle and operating handle therefor rotatable independently of the spindle in one direction, an indicator coaxial with the spindle, slip drive connections between the 100 spindle and indicator for positioning said indicator relatively to the switch and allowing one of the driving parts to rotate independently of the other when power in excess of a predetermined amount is applied to the 105 handle, and means within the indicator for urging the slip-drive connection to its operative position.

Signed at Washington, District of Columbia, this 31st day of July, 1906.
